CLAIM

Jan. 3, 2012 (KR) 30-2012-0000216

The ornamental design for ring for mobile communication terminal, as shown and described.

(51) **LOC (9) Cl.** **08-05**

DESCRIPTION

(52) **U.S. Cl.** **D8/356**

FIG. 1 is a perspective view of ring for mobile communication terminal, showing a new design;

(58) **Field of Classification Search** D8/367,

FIG. 2 is a front elevational view thereof;

D8/371, 373, 354-356, 349; D6/323; 248/215,
248/301, 339, 349.1; 160/349.1, 349.2; 24/265 H,
24/265 R, 599.1, 599.8, 113 R, 573.5; 294/82.18;
29/525.1, 45.3; D3/24; 223/106

FIG. 3 is a rear elevational view thereof;

See application file for complete search history.

FIG. 4 is a left side elevational view thereof;

(56) **References Cited**

FIG. 5 is a right side elevational view thereof;

U.S. PATENT DOCUMENTS

FIG. 6 is a top plan view thereof; and

228,371 A * 6/1880 McAllister 70/27
4,095,316 A * 6/1978 Gabriel 24/599.1
D433,312 S * 11/2000 Luquire D8/333

FIG. 7 is a bottom plan view thereof; and

FIG. 8 is a perspective view thereof showing the ring for mobile communication terminal in an environment in which it may be used.

The broken lines shown in FIG. 8 are included for the purpose of illustrating environmental elements only and form no part of the claimed design.
